(57) CLAIM

The ornamental design for a shoe mounted cleaning accessory, as shown and described.

DESCRIPTION

FIG. 1 is a perspective view of a shoe mounted cleaning accessory.

FIG. 2 is a side view of the shoe mounted cleaning accessory.

FIG. 3 is a front view of the shoe mounted cleaning accessory.

FIG. 4 is an opposite side view from FIG. 2 of the shoe mounted cleaning accessory.

FIG. 5 is a back view of the shoe mounted cleaning accessory.

FIG. 6 is a top view of the shoe mounted cleaning accessory; and,

FIG. 7 is a bottom view of the shoe mounted cleaning accessory.

The broken line showing of the shoe in FIG. 1 is included for the purpose of illustrating the environment of the shoe mounted cleaning accessory and forms no part of the claimed design.
